(57) **CLAIM**

The ornamental design for a robotic arm component, as shown and described.

DESCRIPTION

FIG. 1 is a perspective view of the robotic arm component according to the present invention;

FIG. 2 is a front view of the robotic arm component thereof; FIG. 3 is a back view of the robotic arm component thereof; and,

FIG. 4 is a right side view of the robotic arm component, the left side view being a mirror image thereof.

The broken lines depict unclaimed portions of the robotic arm component and form no part of the claim.
